UNITED STATES PATENT OFFICE.

MYRON J. FERREN, OF STONEHAM, MASSACHUSETTS.

FEED MECHANISM FOR SEWING-MACHINES.

SPECIFICATION forming part of Letters Patent No. 270,185, dated January 2, 1883.

Application filed April 27, 1882. (No model.)

To all whom it may concern:

Be it known that I, MYRON J. FERREN, of Stoneham, in the county of Middlesex and State of Massachusetts, have invented certain 5 Improvements in Feed Mechanism for Sewing-Machines, of which the following is a specification.

This invention relates to that class of sewing-machine feed mechanism whereby the work is reciprocated instead of being moved progressively, so that elongated stitches are formed upon the work first from and then back to a given point, the feed-dog being adapted to serve as a pivot for the work, enabling the operator to rotate the latter and cause the stitches to radiate from a common center and form ornamental designs.

Heretofore in mechanism of this class the feed-dog has had only one movement in each direction—that is to say, after the formation of each stitch the feed-movement has been reversed, so that the designs produced have been limited in depth to the length of a single stitch.

The object of the present invention is to give the feed-dog first a series of steps or movements in one direction and then a corresponding series in the opposite direction, thereby forming first a series of stitches laid end to end from a given point, and then a similar series extending back to said point, thus enabling designs of a greater size or depth to be produced.

To this end my invention consists in the improvements which I will now proceed to describe and claim.

Of the accompanying drawings, forming a part of this specification, Figure 1 represents a front elevation of a portion of a sewing-machine embodying my improvement. Fig. 2 represents an end elevation of the same. Fig. 3 represents a section on line $x-x$, Fig. 2. Figs. 4, 5, and 6 represent respectively sections on lines $y-y$, $z-z$, and $z'-z'$, Fig. 1. Fig. 7 represents a view of a part detached. Figs. 8, 9, and 10 represent stitches formed by the improved mechanism.

The same letters of reference indicate the same parts in all the figures.

In the drawings, A represents the needle, B the shuttle, and C the presser-foot, of a sewing-machine, said parts operating in the usual manner.

D represents the feed-dog, which is formed at its upper end so as to constitute a pivot on which the work may be rotated. The feed-dog 55 is formed upon a bifurcated lever, D', which is connected by a pivot, E, to ears formed on a bent arm, F, the latter being clamped against a stud, G, which projects downwardly from the bed of the machine. The stud G is slotted 60 in its lower end to receive a horizontal stud or bolt, H, which has a shoulder, I, bearing against one side of the stud G, and is threaded at its inner end to engage a nut, J, which bears against the arm F and clamps the latter against 65 the stud G, and at the same time secures the bolt H to said stud.

K represents a sleeve adapted to slide longitudinally on the bolt H, and provided at its inner end with a flange, K', and at its opposite end with a collar, L, which is screwed upon or otherwise rigidly attached to the sleeve K.

M represents a ratchet, which is rigidly attached to the sleeve K; and N represents a plate journaled upon said sleeve so as to rotate independently thereof, and provided with a spring-pawl, O, which engages with the ratchet, as shown in Fig. 5. The plate N is connected by an arm, R, with a crank or eccentric on the driving-shaft S of the machine, 75 said shaft and arm oscillating said plate upon the sleeve K, and causing its pawl to rotate the ratchet M, collar L, and sleeve K step by step.

T represents a collar journaled upon the 85 sleeve K, between the plate N and flange K'. Said collar has vertical dovetail grooves in its opposite sides, in which are slides U U, adapted to move vertically and provided with outwardly-projecting pins or pivots V V, entering orifices 90 in the bifurcations of the lever D'; as shown in Fig. 4. The collar L has a cam-groove, W, cut in its periphery, into which projects a roller, a, on a screw-stud, which is inserted in a casing, b, the latter being secured to the bolt H by 95 means of one or more set-screws, c.

The operation is as follows: The collar L with its cam-groove and attached parts being rotated step by step, as described, the engagement of the roller a with the cam-groove causes 100 the collar L, sleeve K, and the parts supported thereby to receive first a series of longitudinal steps or movements in one direction and then a similar series in the opposite direc-

tion, the stud on which the roller *a* is placed being fixed and the cam having a diagonal direction and being made up of a series of curves, so formed that the endwise motion caused by its engagement with the roller will be intermittent, the movements being continued in one direction during the first half rotation of the collar *L* and reversed during the last half. It will be seen that the described engagement to of the lever *D'* with the collar *T* causes said lever, with the feed-dog, to move with the collar *L*, sleeve *K*, and accompanying parts, and thus move the work resting on the feed-dog first a series of steps in one direction and then a similar series of steps in the opposite direction. The steps are so timed relatively to the operation of the stitch-forming mechanism that the work will be moved only when the needle is raised. The stitches 3 are therefore laid upon the work in a series extending from a given point outwardly, and then in a similar series back to said point, as shown in Fig. 8. After each outward and returning series has been formed the operator turns the work on the feed-dog, the latter acting as a pivot, so that the next series of stitches will diverge from the first, and so on. A circular design, as shown in Fig. 9, or a segmental or fan-shaped design, as shown in Fig. 10, may thus be formed, each design having a depth or distance from the inner to the outer point considerably exceeding that of any design which can be produced by single stitches as heretofore. The designs are also more durable than those heretofore made, because the individual stitches are not so long and loose. Boot or shoe uppers and many other articles in leather, cloth, and other materials may be ornamented in this manner.

I prefer to employ a spring-brake, *h*, bearing upon the periphery of the collar *L*, to prevent the latter from being rotated farther than the length of one of the ratchet-teeth at a time, said brake being a metal spring secured at one end to a fixed support and pressing with its free end a piece of leather or other suitable material against the collar *L*.

I am aware that a feed dog or device adapted to give the work the usual progressive movement has been provided with mechanism to move it laterally in a series of steps from the needle, and then a similar series of steps toward the needle; but such device gives the work a compound movement and produces a zigzag arrangement of stitches wholly unlike mine.

I am also aware that a feed-dog adapted to serve as a pivot for the work and to reciprocate the work by a single movement in each direction is not new, as before stated.

60 The arm *F*, to which the lever *D'* is pivoted,

is made vertically adjustable by means of a slot, *F'*, as shown in Fig. 3. By raising or lowering said plate the length of each movement of the feed-dog will be increased or diminished, as will be readily seen.

The casing *b* is adjustable upon the bolt *H*, and is held by its set-screw *c* at any point to which it may be adjusted. By moving said casing the starting-point of the feed-dog may be brought nearer to or farther from the needle. 70

I claim—

1. The combination, with the stitch-forming mechanism of a sewing-machine, of a feed-dog adapted to serve as a pivot for the work resting upon it, and mechanism, substantially as described, to impart to said feed-dog, first, a series of substantially horizontal steps in one direction, and then a similar series in the opposite direction, whereby a series of elongated stitches are laid upon the material from a given point, and another series back to said point, as set forth. 75

2. The combination, with the feed-dog and its pivoted supporting-lever *D'*, of the horizontally-movable collar *T*, having vertically-movable slides *U U*, engaged with the lever *D'*, and means, substantially as described, for giving said block first a series of steps or movements in one direction and then a similar series in the opposite direction, thereby oscillating the lever *D'* and the feed-dog intermittently, as set forth. 80

3. The combination, with the feed-dog, supporting-lever, and the collar *T*, having slides *U U*, engaged with said lever, of the vertically-adjustable arm *F*, to which said lever is pivoted, and means for positively holding said arm in any position to which it may be adjusted, as and for the purpose set forth. 95

4. The combination, with the feed-dog and its pivoted supporting-lever, of the horizontally-movable collar *T*, engaged, as described, with the lever, the collar *L*, having the cam-groove *W* and adapted to rotate independently and to move horizontally with the collar *T*, and the casing *b*, having a stud or roller engaging with the cam-groove, said sleeve being horizontally-adjustable and provided with means for positively holding it in any position to which it may be adjusted, whereby the initial position or starting-point of the feed-dog may be regulated, as set forth. 100

In testimony whereof I have signed my name to this specification, in the presence of two subscribing witnesses, this 15th day of April, 1882. 110

MYRON J. FERREN.
